DRAFTING TEMPLATE

Harry L. Kellinger, Los Angeles, and Jack Milburn, Santa Barbara, Calif., assignors to Douglas Aircraft Company, Inc., Santa Monica, Calif.

Filed July 10, 1964, Ser. No. 80,808

Term of patent 14 years

(Cl. D52—6)

The single figure of the drawing is a top plan view of a drafting template showing our new design.

The template is of conventional thickness, and the bottom of the template is plain in appearance.

WE CLAIM:

The ornamental design for a drafting template, as shown and described.
